Specification of Letters Patent.

Patented July 7, 1914.

Original application filed March 30, 1908, Serial No. 424,225. Divided and this application filed October 27, 1911. Serial No. 657,135.

To all whom it may concern:

Be it known that I, ORRELL ASHTON, a citizen of the United States, residing at Swampscott, in the county of Essex and State of Massachusetts, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for use in the manufacture of boots and shoes, particularly welt shoes, and is a division of my application Serial No. 424,225, filed March 30, 1908, which said application matured June 25, 1912 into Patent No. 1,030,762.

In making welt shoes the upper is laid over the thinned marginal portion or feather edge of the innersole and against the shoulder or lip of the innersole and is temporarily fastened by a wire or other continuous binding material at the toe while at the sides of the shoe the upper is secured by partially driven tacks inserted through the upper into the innersole in or adjacent to the angle between the lip and the feather edge. Subsequently the upper is permanently fastened to the innersole in the inseam sewing operation by stitches which pass through the upper into the innersole, and for the purpose of obtaining and securing a tight seam it is desirable that the stitches pass through the upper into the innersole close down to the base of the lip.

An object of this invention is to prepare the lasted shoe for the inseaming operation by creasing the upper stock snugly down into the angle between the feather and the lip of the innersole so that the stitches may pass deeply into the innersole at the base of the lip and the upper be tightly drawn by the stitches against the adjacent faces of the innersole. In addition to the advantages of the tight and secure seam gained by the use of this invention, the fact that the stitches can be located low down enables the shoe to be trimmed after the inseaming operation, close to the surface of the middle portion of the sole so that the shoe requires less filling material in the middle portion of the sole than would otherwise be needed.

A feature of this invention consists in the provision in a machine for working on a lasted welt shoe, of improved means for creasing the upper into the angle between the lip and feather edge of the innersole. In the illustrated embodiment of the invention the creasing tool performs its work by a beating and rubbing operation, the tool being actuated to act by impact against the upper standing against the lip and to have a rubbing and pressing action upon the upper material lying upon the feather or marginal portion of the innersole from its edge to the lip. To this end the creasing tool is shown as connected to a reciprocating carrier by which it is moved in substantially the plane of the shoe bottom from and toward the lip while the shoe is held up against the lower side of the tool, the creasing tool being preferably vibrated with sufficient rapidity to cause said tool to deliver repeated blows against each portion of upper. The length of the reciprocating movements may be less than the width of the marginal portion of the shoe bottom so that the creasing tool remains in continuous contact with the shoe. The striking face of the creasing tool will preferably be shaped to engage and crowd or beat downwardly as well as inwardly the wire which binds the upper in the angle of the innersole about the toe. To this end the tool is herein shown with a beveled or inclined lower edge on its end face. This acts at each blow to wedge the wire farther downwardly and seat or embed the wire in the upper and thereby crease the upper into the angle. A further function which may be performed by the creasing tool, in addition to forcing the upper into the angle of the innersole, is that of smoothing and compacting the upper stock upon the feather of the innersole so that the welt which is laid upon this marginal portion of the shoe bottom and secured in the inseaming operation shall find a smooth surface of upper material upon which to lie and will be positioned and attached snugly with relation to the marginal portion of the innersole thus presenting a close and tight welt crease between the body of the shoe and the upper face of the welt in the finished product.

A further feature of this invention consists in novel combinations with a creasing

tool arranged as above suggested, or otherwise, of a guide for engaging the bottom of the shoe. This guide will preferably be arranged to position the shoe both vertically and laterally with relation to the creasing tool and in the preferred construction here-with illustrated the guide forms an abutment engaging the bottom face of the inner-sole and the inner face of the lip of the innersole. The guide is preferably located in position to form an abutment between which and the creasing tool the lip of the innersole and the upstanding upper material are gripped or pinched in the reciproca-tion of the tool. By this means danger of the creasing tool bending the lip from its upright position is obviated and instead the lip and the upper material standing against it are formed or reshaped into an upright position to receive to the best ad-vantage the operation of the inseaming ma-chine. The creasing tool may advan-tageously be yieldingly actuated whereby to accommodate itself to the difference in the thickness of the upper material and lip, commonly called the between substance, at different portions of the shoe. Preferably, and as herein shown, the shoe guide or abutment is a driven roll turning about an axis substantially perpendicular to the shoe bot-tom in the direction to feed or assist in feed-ing the shoe for the operation of the creas-ing tool progressively around the shoe. Also preferably, the roll will be provided with ribs or grooves on its periphery ex-tending oblique to its direction of rotation and arranged to tend to lift or work up-wardly the portion of the innersole lip with which it contacts. By these means the lip is straightened up into position to receive the inseaming operation in case the lip for any reason does not stand upright, as for example, in case the lip has not been prop-erly turned up or has been bent or battered down in the lasting or other preceding op-eration. It is recognized as desirable to beat or smooth the side of the shoe at and adja-ent to the edge of the shoe bottom at which portion slight wrinkles or inequalities are sometimes found after the lasting operation. This beating or smoothing operation, com-monly termed "blocking", is designed to take out any such inequalities and conform the contour of the shoe accurately to the contour of the side of the last at this por-tion.

In accordance with a further feature of this invention, means is provided for block-ing the shoe during the operation of the creasing tool. As herein illustrated, a block-ing tool is mounted for movement with the creasing tool and is arranged to act upon the side of the shoe from its edge downwardly while the creasing tool acts upon the bottom of the shoe from its edge inwardly. These

two tools therefore, between them, shape or form the upper to the last at and adjacent to the edge of the shoe bottom and produce a shoe having at this portion a contour of its outer surface corresponding to the shape 70 of the under-lying faces of the last. As herein shown, the blocking tool is yieldingly attached to the carrier upon which the creasing tool is unyieldingly mounted. The stroke of the carrier will cause the blocking 75 tool to be retracted from the side of the shoe and the creasing tool retracted from the upper standing against the lip of the innersole so that these tools may act by im-pact against these surfaces of the shoe, al-though the creasing tool is not necessarily, and preferably is not, retracted beyond the edge of the shoe so that it does not leave contact with the shoe bottom.

It is usually desirable to trim away the 85 upstanding upper material after the shoe has been lasted and before the inseam trim-ming operation. Accordingly, means are provided for trimming off the projecting edges of the vamp and lining while the 90 blocking and creasing tools are acting re-spectively upon the side and bottom of the shoe. In the machine shown as embodying the invention, these vamp trimming means comprise a stationary knife and a co-operat-ing reciprocating knife and, in accordance with a further feature of the invention, con-nected mechanism is provided for operating both the reciprocating knife and the carrier upon which are mounted the creasing tool 100 and the blocking tool.

These and other features and advantages of the present invention will be fully set forth in the following detailed description of so much of a machine embodying the 105 present invention as is necessary for an un-derstanding thereof and will then be de-fined in the appended claims.

Referring to the drawings: Figure 1 is a side view in elevation of a machine embody-ing the present invention; Fig. 2 is a view similar to Fig. 1 and showing a modifica-tion; Fig. 3 is a plan view; and Fig. 4 is a vertical sectional detail showing the operat-ing tools and their operative relation to the 115 shoe being treated.

The frame of the machine supports a driving shaft 2 having an eccentric em-braced by a strap 4, as shown in dotted lines in Figs. 1 and 2. This strap is con-nected to a reciprocating bar 6 that carries a knife 8 adjustably secured in position thereon by the bolt 10. The knife 8 co-operates with a fixed knife 12 suspended by a bracket 14 from the overhanging arm 15 of the frame and also supported by the shaft 16 which passes through it and is provided below the knife 12 with the feed roll 18. The shaft 16 is driven by a worm gear 20, meshing with a worm on the shaft 22 which 125 130

is driven by a belt 24 from a pulley on the shaft 2. The feed roll is provided on its periphery with ribs, as at 25, which tend to lift the vamp or lining with which they contact into position to be acted upon by the cutters. The ribbed roll also tends to feed the shoe in the direction in which the operation is progressing. The roll 18 is formed as a truncated cone having its smaller end 5 position to contact with the insole and constitutes a rest about which the shoe may be tipped to vary the presentation of the shoe according to the contour of the particular portion of the shoe being blocked.

10 The blocking tool, indicated at 60, is shown in Fig. 1 mounted upon the knife bar 6. In this construction, the bolt 10 secures upon the bar 6 a carrier 62 in which the blocking tool 60 is yieldingly mounted 15 and arranged to slide forwardly and backwardly. The tool is held in its foremost position by a spring 64 pressing against a stud 65 projecting inwardly from the blocking tool 60 through a slot in the carrier 62.

20 In this construction it will be understood 25 that the blocking tool is operative at all times when the trimmer is in use.

The carrier 62 is provided with an end portion 66 (Figs. 1, 2 and 4) adapted to 30 project outwardly beyond the blocking tool 60 when the latter is in its backwardly pressed position and to overlie the marginal portion of the shoe bottom at such times. The reciprocating member 66 which thus 35 forms a third tool preferably projects over the shoe bottom far enough to press the vamp against the outer face of the lip 55 of the innersole. The lip abuts on its opposite side against the feed roll 18 and the 40 member 66 therefore serves to crease the upper material into the angle between the feather edge of the innersole and the outer face of the lip and to beat the upper against said outer face of the lip, while the roll 18 45 forms an abutment for the inner face of the lip. The pin 65 and slot connection (Fig. 4) limit the projection of the member 66 beyond the blocking tool 60 to substantially the width of the feather of the 50 innersole. Preferably, too, the eccentric embraced by the strap 4 in the first construction (Fig. 1) and the cam 30 of the second construction (Fig. 2) are formed and arranged so to limit the backward or return 55 movement of the member 66 that in its retracted position the member 66 is not entirely withdrawn from engagement with the feather edge of the innersole. The result is that the creasing tool 66 is moved 60 in a path corresponding substantially to but slightly less in extent than the usual width of the said feather edge so that during its operation the creasing tool remains in continuous shoe guiding contact with the shoe. 65 The creasing tool 66 thus acts as a height

gage for the shoe, insuring by its continuous engagement with the feather edge of the shoe that it will not strike against or mar the upper at the edge of the shoe or override and thus batter or break down the 70 lip of the innersole, as might happen if the shoe were not held by the operator at all times at the right height and angle relatively to the said tool 66. When the vamp is bound in position by a wire 68, as is 75 usual, the member 66, which for the purpose of identification will be called the creasing tool, serves to force or beat the wire into holding position. To this end it may be formed with an inclined face 69 to crowd 80 the binder downwardly as well as inwardly into position to hold the upper in the angle between the lip and feather edge of the innersole. By forcing the wire, and thereby the upper, snugly into the angle a tighter 85 inseam can be formed in the subsequent inseam sewing operation.

In the modified construction shown in Fig. 2, the carrier 62 upon which are mounted the blocking tool 60 and the creasing tool 66, is supported by a separate slide from that which carries the trimming knife 8, and the blocking tool 60 and the creasing tool 66 are actuated and controlled independently of the knife 8 so that, when desired, the 90 blocking hammer 60 may remain at rest while the trimming knife 8 is reciprocated. In this construction, the shaft 2, has, in addition to the eccentric embraced by the strap 4 connected to the reciprocating knife bar 95 100 6, a cam 30 having in its side a groove 32, which at its inner edge is concentric with the shaft and at its outer edge is eccentric through a portion of its length, forming at 34 a drop leading to a concentric portion 36. 105 Standing in this groove is roll 38 on a reciprocating bar 40 that carries at its front end the blocking tool 60. Projecting laterally from the bar 40 through a slot in the frame is a stud 44 embraced by the slotted 110 upright arm of an angle lever 45. This lever, which is pivoted at 46, has an opening through which extends the treadle rod 48 connected to the treadle 50. A spring 52 is interposed between the head of the rod and the upper face of the horizontal arm of the angle lever. A light spring 54 connects the rear side of the angle lever with the frame and holds this lever rocked backwardly with the roll 38 normally against the concentric 115 inner wall of the cam groove. When the roll is in this position the blocking hammer remains at rest while the trimming knife 8 is reciprocated. By depressing the treadle 50 the roll 38 is forced against the outer wall 120 of the groove and as the high point 34 passes the roll the blocking hammer is actuated toward the shoe with a force dependent upon the extent to which the spring 52 has been compressed. By depressing the treadle and 125 130

compressing the spring 52 more or less the strength of the blows of the hammer can be varied during the trimming operation and entirely independent of that operation. The 5 treadle 50 may be depressed to start the blocking hammer either when the shoe is first inserted so that the blocking operation will begin at the point where the trimming begins or the treadle may be depressed later 10 in the trimming operation to cause the blocking operation to begin at any desired point.

In the use of the machine the workman presents the shoe in the position shown in 15 Fig. 1 with the face of the innersole against the lower end of the feed roll 18 and preferably with the inner face of the lip 55 against the periphery of the roll. By the reciprocation of the knife 8 the projecting 20 edges of the vamp and lining are trimmed as shown. While the feed roll has a tendency to advance the work in the direction in which the operation is progressing the workman holding the shoe in his hands controls 25 the rate at which the shoe is advanced and can hold the shoe stationary at any particular point while the blocking hammer thoroughly beats the upper on the side of the shoe at any places that require special treatment. In this way wrinkles or inequalities 30 in the side of the shoe can be quickly beaten out.

It is to be observed that the blocking hammer is formed on its outer acting face 35 to engage the side of the shoe at and adjacent to its edge and preferably the hammer extends slightly above the edge of the shoe and also extends downwardly along the side of the shoe for some distance.

Having explained this invention and described in what manner the same may be embodied, I claim as new and desire to secure by Letters Patent of the United States:—

1. A machine of the class described, having in combination, means for removing surplus material from the projecting edges of the vamp of a lasted shoe, a creasing tool, and connected mechanism for actuating the 50 tool and said means.

2. A machine of the class described, having, in combination, vamp trimming means comprising a reciprocating knife, combined with a blocking tool carried by the knife 55 and arranged to beat the side of the shoe while the knife cuts the vamp.

3. A machine of the class described, having, in combination, vamp trimming means comprising a reciprocating knife, combined 60 with a blocking tool yieldingly carried by the knife for beating the side of the shoe below the knife.

4. A machine of the class described, having, in combination, vamp trimming means

comprising a reciprocating knife, combined 65 with a blocking tool arranged to be actuated with the knife.

5. A machine of the class described, having, in combination, vamp trimming means comprising a reciprocating knife, combined 70 with a blocking tool for beating the upper on the side of a shoe, and means for forcing the upper into the angle of union between the lip and feather edge of the shoe inner-sole.

6. A machine of the class described, having, in combination, vamp trimming means comprising a reciprocating knife, and means for forcing the upper into the angle of union 80 between the lip and feather edge of the shoe innersole.

7. A machine of the class described, having, in combination, vamp trimming means comprising a reciprocating knife, and means for forcing the upper into the angle of union 85 between the lip and feather edge of the shoe innersole, said forcing means having a face formed to crowd the binding wire downwardly as well as inwardly into holding position.

8. A machine of the class described, having, in combination, means for trimming the upper of a lasted welt shoe at the top of the innersole lip, and means arranged for reciprocation over the shoe bottom to press the 95 upper into the angle between the lip and the feather edge of the shoe innersole and position it for the trimming operation.

9. A machine of the class described, having, in combination, upper trimming means, 100 means for shaping the side of a shoe, and means arranged for reciprocation over the shoe bottom and formed to crowd the binder of a lasted welt shoe downwardly and inwardly into position to hold the upper in the 105 angle between the lip and feather edge of the shoe innersole.

10. A machine of the class described, having, in combination, a reciprocating blocking tool for beating the side of a shoe, and means arranged for reciprocation over the shoe bottom to press the upper of a lasted welt shoe against the outer face of the lip of the shoe innersole, and an abutment for the 110 opposed inner face of said lip.

11. A machine of the class described, having, in combination, means for shaping the side of a shoe, a creasing tool arranged to be moved in the plane of the shoe bottom to press the upper into the angle between the 120 feather edge and lip of the innersole, means arranged to engage the shoe bottom inside the innersole lip to assist the operator in positioning the shoe for the described action of the creasing tool, and means for imparting to the creasing tool reciprocating movements in a path shorter than the width of the feather edge of the innersole, whereby 125

- said creasing tool remains in continuous shoe guiding contact with the shoe during its operation.
12. A machine of the class described, having, in combination, a tool for creasing the upper into the angle between the feather edge and lip of the innersole and means for positioning a shoe relatively thereto comprising a roll constructed and arranged to engage the bottom of a welt shoe at the inner side of the lip. 65
13. A machine of the class described, having, in combination, a tool for pressing the upper of a lasted shoe into the angle formed by the feather edge and the outer face of the lip of a welt shoe innersole, and an abutment for the opposed inner face of the lip. 70
14. A machine of the class described, having, in combination, a creasing tool for pressing the upper of a lasted shoe into the angle formed by the feather edge and the lip of a welt innersole and a guide for engaging the bottom of the shoe arranged to position the shoe vertically and laterally with relation to the creasing tool. 75
15. A machine of the class described, having, in combination, a reciprocating blocking tool for beating the side of a shoe, a reciprocating creasing tool to press the upper into the angle between the feather and lip of the innersole, and a rest comprising a truncated cone having its smaller end in position to contact with the bottom face of the innersole in position to permit tipping the shoe about the said rest to vary its presentation to the action of the blocking and creasing tools. 80
16. A machine of the class described, having, in combination, a creasing tool for pressing the upper into the angle between the feather edge and lip of the innersole, means for positioning a shoe relatively thereto comprising a roll, constructed and arranged to engage the inner side of the lip of the innersole, and means for actuating the roll in the direction to feed the shoe past the creasing tool. 85
17. A machine of the class described, having, in combination, a creasing tool for pressing the upper of a lasted shoe into the angle between the feather edge and lip of the innersole, a roll arranged to engage the inner side of the lip of the innersole and mounted to turn about an axis substantially perpendicular thereto and means for operating the roll in a direction to feed the shoe for the operation of the creasing tool progressively around the shoe. 90
18. A machine of the class described, having, in combination, a creasing tool for pressing the upper of a lasted shoe into the angle formed by the feather edge and lip of the innersole, a roll for engaging the bottom face of the innersole and the inner face of the lip of the innersole and provided about its periphery with ribs or grooves extending obliquely to its direction of rotation and arranged to work upwardly the portion of the lip with which the roll contacts, and means for rotating the roll. 95
19. A machine of the class described, having, in combination, an abutment for the inner face of the lip of a welt shoe innersole, a creasing tool for forcing the upper against the outer face of the lip, and means for rapidly vibrating said tool toward and from said lip to cause said tool to deliver repeated upper creasing blows against each portion of the work. 100
20. A machine of the class described, having, in combination, a positioning roll for engaging the inner face of the lip of a welt shoe innersole, a creasing tool having a backwardly inclined face shaped to crowd the binder of a lasted shoe downwardly and inwardly into position to hold the upper in the angle between the lip and the feather edge of the innersole, and means for actuating the tool. 105
21. A machine of the class described, having, in combination, a blocking tool, a carrier therefor, means for imparting to the tool a right-line reciprocating movement to beat the side of the shoe at and adjacent to its edge, and a creasing tool mounted for movement therewith and arranged in a plane to press the upper on the last bottom inwardly from the edge of the last and downwardly into the angle between the lip and the feather edge of the inner sole. 110
22. A machine of the class described, having, in combination, means for trimming the upper at the top of the lip of the innersole of a lasted shoe, a tool arranged to be actuated to act by impact against the upper standing against the lip of the innersole for positioning the upper for the trimming operation and to have a rubbing and pressing action upon the upper material lying upon the feather of the innersole from its edge to the lip, and operating means for said last named tool. 115
23. A machine of the class described, having, in combination, a blocking tool, a carrier therefor, means for imparting to the tool a right-line reciprocating movement to beat the side of the shoe at and adjacent to its edge, a creasing tool mounted for movement therewith and arranged in a plane to crease the upper on the last bottom inwardly from the edge of the last, yielding connections between the tools, and means to limit the movement of the creasing tool beyond the blocking tool to substantially the width of the feather of the innersole. 120
24. A machine of the class described, having, in combination, a reciprocating carrier, a blocking tool yieldingly mounted on the 125

carrier, a presser on the carrier, and means for actuating the carrier to drive the blocking tool against the side of the shoe to shape the upper to the side of the last and then 5 advance relatively to the blocking tool to project the presser over the bottom of the shoe to shape the upper into the angle between the feather and the lip of the inner- 10 sole, and a cutter to trim the upstanding edge of the upper after it has been so shaped.

25. A machine of the class described, having, in combination, a reciprocating carrier, a blocking tool yieldingly mounted on the carrier, a presser on the carrier, means for actuating the carrier to drive the blocking tool against the side of a lasted shoe and then advance relatively to the blocking tool to project the presser over the shoe bottom to force the upper against the shoulder 15 formed by the lip of a welt innersole, and an abutment for the opposite side of the lip.

20. A machine of the class described having, in combination, vamp trimming means comprising a reciprocating knife, a shaping 25 tool arranged to operate on the side of a shoe substantially at its edge, and a shaping tool operating on the bottom of the shoe at and adjacent to its edge and having a forward movement inwardly in the plane of the shoe 30 bottom through a predetermined distance beyond the operative position of the side shaping tool to press the upper into the angle between the feather and the lip of a welt shoe innersole the bottom shaping tool thereafter 35 having a return movement in approximately the same path and less than the width of the feather whereby the bottom shaping tool is in continuous engagement with the upper on the feather.

27. A machine of the class described having, in combination, vamp trimming means comprising a stationary knife and a coöperating reciprocating knife, a shaping tool operating on the side of a shoe at and adjacent to its edge, a shaping tool operating on the 45 bottom of a shoe at and adjacent to its edge and having a movement inwardly in the plane of the shoe bottom to press the upper into the angle between the feather and the 50 lip of a welt shoe innersole, said machine being arranged so to limit the movement of the bottom shaping tool that the bottom shaping tool will move inwardly only to the inner- 55 sole lip and that the bottom shaping tool upon its return movement will not be withdrawn from engagement with the upper on the feather of the innersole.

28. In a machine of the class described, a shaping tool adapted to engage a lasted welt shoe in the angle between the upper which overlies the feather of the innersole and the upper which stands against the lip of the innersole and to crease the upper into said angle, means for vibrating said tool laterally toward and from said lip, and means engaging the shoe bottom and coöperating with the lower face of said tool to position the shoe with the plane of the shoe bottom substantially parallel with the plane in which the tool is vibrated.

In testimony whereof I have signed my name to this specification in the presence of two subscribing witnesses.

ORRELL ASHTON.
